UNITED STATES PATENT OFFICE.

WILLIAM MAX BOENSCH AND TRUMAN BELDEN WEAVER, OF SAN FRANCISCO,
CALIFORNIA.

WAREHOUSE-TRUCK.

1,126,368.

Specification of Letters Patent.

Patented Jan. 26, 1915.

Application filed December 6, 1913. Serial No. 805,171.

To all whom it may concern:

Be it known that we, WILLIAM MAX BOENSCH and TRUMAN BELDEN WEAVER, citizens of the United States, residing in the city and county of San Francisco and State of California, have invented certain new and useful Improvements in Warehouse-Trucks, of which the following is a specification.

10 The present invention relates to elevating and conveying trucks and more particularly to a type of truck adapted for the handling and piling of rolls of paper in warehouses or other places of storage, and the invention has for its principal objects to provide a truck by the use of which the rough handling and rolling of the rolls of paper will be eliminated, one provided with an elevating frame for receiving and elevating the rolls for stacking, and one provided with a means associated with the elevating frame for tipping the roll thereon and retaining the same thereon while being elevated.

25 With the above mentioned and other objects in view, the invention consists in the construction and novel combination of parts hereinafter described, illustrated in the accompanying drawing and pointed out in the 30 claims hereto appended; it being understood that various changes in the form, proportion, size and minor details of construction within the scope of the claims may be resorted to without departing from the 35 spirit or sacrificing any of the advantages of the invention.

To more fully comprehend the invention, reference is directed to the accompanying drawing, wherein—

40 Figure 1 is a view in front elevation of my invention with the roll engaging means thrown into a vertical position. Fig. 2 is a view in side elevation disclosing the supporting frame, the sliding frame mounted thereon, the roll engaging means mounted on the sliding frame, and the means for operating the roll engaging means and the sliding frame. Fig. 3 is a vertical sectional view of a truck with the nose of the sliding frame beneath a roll of paper and the roll engaging means over the top of the roll in a position to pull the same onto the sliding frame.

Referring more particularly to the draw-

ings, wherein like characters of reference 55 designate corresponding parts throughout the several views—1 indicates the side frame members of the supporting truck having rearwardly inclined front guide faces 2, and being connected in spaced relation with each 60 other by the top member 3, the back brace 4, and the rearwardly curved lower brace 5.

Supporting wheels 6 are mounted on axles 7 at the lower forward end of each side frame member and the axles are supported at their 65 ends by the braces 8 connected thereto and to the side frame members and suitable caster wheels 9 are carried by the lower rear end of said frame members.

Suitable operating handles 10 extend rearwardly from the side frame members and the same assist in moving the supporting truck from one place to another.

Slidably mounted on the front faces 2 of the side frames are the transverse members 11 of the elevating frame or platform which are formed at their ends with hooked portions 12 which operate in the longitudinal grooves 13 formed in the outer side walls of the front faces 2 and maintain the elevating frame or platform in position. The transverse members 11 are connected by the upper end portions 15' of a nose 15, and are braced by the frame 16.

Projecting upwardly from the upper 85 member 11 is a frame 16' to which is hinged, as at 17, the inner end of a guide bar 18 carrying adjacent its outer end longitudinally disposed headed bolts 19 which operate in elongated longitudinally disposed 90 guides 20 formed in a slidably engaging member 21 which is formed at its outer end with an engaging lip 22 and carries at its inner end a suitable eye 23.

A flexible connection 24 is connected at 95 one end to the eye 23 and is preferably spliced at its opposite end into a flexible connection 25 which is connected at one end to an eye 26 on the frame 16, and extends over a pulley 27 supported by the top member 3 100 and winds at its opposite end about a drum 28 carried by a rotatable shaft 29 journaled in bearings 30 carried by the side frame members. The flexible connections are of such length that when the sliding frame or 105 platform is in its lowermost position and the slidably engaging member is extended over the outer edge of the roll and the drum

is rotated to wind, that the the slidable engaging member will be drawn inwardly to tightly position the roll on the slidable frame before the frame is elevated.

5 The shaft 29 carries a toothed gear 31 which intermeshes with a drive gear 32 carried by a shaft 33 rotatably supported by the frame and said shaft is squared at its ends, as at 34, to receive the operating handles 35. A ratchet 36 is carried by the shaft 10 29 and the same is adapted to be engaged by a pivoted pawl 37, to prevent the shaft from rotating freely in a direction which will permit the sliding frame to move downwardly.

15 When the device is to be used to engage a roll of paper and elevate the same to a position to be stacked upon another roll, the flexible cable is unwound from the drum, 20 permitting the sliding frame or platform to assume its lowermost position, which also permits the slidable engaging member to be extended its full length. The truck is now positioned adjacent the roll to be elevated, 25 and the roll is tipped slightly to permit the nose 15 to be forced under the roll, the engaging lip is positioned over the outer edge of the roll, as in Fig. 3, and the operator now operates the handle 35 to wind the 30 flexible connection on the drum. The winding of the flexible connection on the drum first causes the engaging member to be drawn inwardly which will draw the roll onto the frame and the same is supported thereon by 35 the nose 15 and the engaging member 21 and lip 22. Further winding of the connection about the drum will cause an upward pull on the elevating frame or platform, and the same together with the roll will be elevated 40 relative to the truck frame, and after the frame has been elevated to the proper height, the truck carrying the roll is pushed up to a positioned roll and the spaced side frame members and the rearwardly curved lower 45 brace member will permit the truck frame to be advanced relative to the lowermost roll so that the elevated roll may be positioned thereover and when the elevated roll is so positioned, the lip of the engaging member is disengaged 50 from the elevated roll by forcing the engaging member upwardly with a sharp blow from beneath, which will permit the elevated roll to rest on the upper end of the lower roll.

55 It will be apparent that by employing a structure as above described, the piling of the rolls will be expedited over the method now in use of rolling the same up an incline, that the damage to the rolls over the present 60 method of piling will be overcome, and a greater number of rolls may be piled with fewer operators than are required to roll a single roll up the incline to pile the same by the present method.

65 Having thus described my invention what

I claim as new and desire to protect by Letters Patent is:—

1. A truck comprising a vertically extending frame provided with inclined guides, a supporting platform movable along said guides, means for raising and lowering said platform, devices operatively associated with said platform, means for holding the articles to be supported in position relative to the platform, said platform raising means actuating said device in advance of the raising of the platform.

2. A truck comprising a frame provided with upwardly extended rearwardly inclined guides, a supporting platform movably mounted thereon, mechanism within the frame for raising and lowering the said platform, and means associated with said mechanism and operated thereby for engaging the upper edge portion of the article to be transported and swinging the same toward the supporting platform, said means participating in the movement of said platform.

3. A warehouse truck comprising a vertically extended frame provided with inclined guides, a supporting platform movably mounted thereon, mechanism within the frame for raising and lowering said platform, manually operated means carried by the platform and operated by said mechanism for engaging the upper edge portion of the article to be transported and for retaining the same in position thereon during the movement of said platform, the article 100 engaging means acting in advance of the movement of the platform.

4. A truck comprising a frame provided with upwardly extended guides, a supporting platform movably mounted thereon, and mechanism within the frame for raising and lowering said platform, a guide hinged to said platform, article engaging means slideable on said guide for engaging the upper edge portion of the article to be transported, and connections associated with said frame operating mechanism for operating said article engaging means to swing the article toward the supporting platform.

5. A ware-house truck comprising a frame provided with upwardly extended rearwardly inclined guides, a supporting platform movably mounted thereon, mechanism within the frame for raising and lowering said platform, a guide hinged to said platform, article engaging means slideable on said guide for engaging the upper edge portion of the article to be transported, and connections associated with said frame operating mechanism for operating said article engaging means to swing the article toward the supporting platform.

6. A ware-house truck comprising a frame provided with upwardly extended rearwardly inclined guides, a supporting plat-

form movably mounted thereon, a guide hinged to said platform, article engaging means slidable on said guide for engaging the upper edge portion of the article to be transported, a drum rotatably mounted on the frame, means for operating said drum, a connection between said drum and platform for raising and lowering the same on the rotation of said drum, and a connection between said last mentioned connection and said article engaging means for operating

the same to swing the article toward the supporting platform.

In testimony whereof we have signed our names to this specification in the presence of 15 two subscribing witnesses.
